United States Patent

Des. 237,675
Patented Nov. 18, 1975

237,675

BASKET

John J. Cameron, Ottawa, Ontario, Canada, assignor
to Jayscam Industries, Limited, Unionville, Ontario,
Canada

Filed July 11, 1973, Ser. No. 378,131

Claims priority, application Canada May 24, 1973

Term of patent 14 years

Int. Cl. D7—07

U.S. Cl. D7—189

FIG. 1

FIG. 2

FIG. 1 is a perspective view of a basket showing my new design, the end and side not fully shown being identical respectively to the end and side shown therein; and

FIG. 2 is a top plan view thereof.

I claim:

The ornamental design for a basket, as shown and described.
